Des. 190,118
Patented Apr. 18, 1961

190,118

HUB CAP

John J. Palotsee, 330 E. Front St., Youngstown, Ohio

Filed Mar. 15, 1960, Ser. No. 59,736

Term of patent 14 years

(Cl. D14—30)

FIG. 1

FIG. 2

I claim:

The ornamental design for a hub cap, as shown.
